DESIGN FOR A HOT LINE TAP

Stephen P. Becker, Poughkeepsie, N. Y.

Application March 23, 1946, Serial No. 127,881

Term of patent 7 years

(Cl. D26—1)

To all whom it may concern:

Be it known that I, Stephen P. Becker, a citizen of the United States, residing in Poughkeepsie, county of Dutchess, State of New York, have invented a new, original, and ornamental Design for a Hot Line Tap, of which the following is a specification, reference being had to the accompanying drawing, which forms a part thereof.

Fig. 1 is a rear elevational view of a hot line tap, showing my new design;

Fig. 2 is a side elevational view; and

Fig. 3 is a front elevational view thereof.

I claim:

The ornamental design for a hot line tap, as shown.

STEPHEN P. BECKER.
